UNITED STATES PATENT OFFICE

158,158

HAND SLED

Louis Vavrik, Rossford, Ohio, assignor to The
Kalamazoo Sled Company, Kalamazoo, Mich.

Application December 9, 1948, Serial No. 150,050

Term of patent 14 years

(Cl. D34—15)

To all whom it may concern:

Be it known that I, Louis Vavrik, a citizen of the United States, residing at Rossford, in the county of Wood and State of Ohio, have invented a new, original, and ornamental Design for Hand Sled, of which the following is a specification, reference being had to the accompanying drawing, forming part thereof.

Fig. 1 is a plan view, and

Fig. 2 is a side elevational view of a hand sled showing my new design.

I claim:

The ornamental design for a hand sled, as shown.

LOUIS VAVRIK.
